troit, Mich., a corporation of Michigan

Application April 28, 1945, Serial No. 590,796

4 Claims. (Cl. 91—46)

1

This invention relates to apparatus for processing rope and has for its principal object the provision of apparatus of this type by means of which rope may be impregnated and dried in a quick and economical manner.

Objects of the invention include the provision of means for submerging rope in a bath of treating composition, then removing it therefrom and drying the rope; the provision of apparatus as above described in which a rope is continuously fed through the treating composition and then over spaced drums where it is dried; the provision of apparatus as above described in which the rope is passed around spaced drums within a bath of the treating composition or solution, the drums being readily removable from the bath for the purpose of applying a new run of rope thereto; the provision of a construction as above described in which the drums in the bath are mounted in a frame and supported at one end only on the frame whereby to provide open ends facilitating the winding of the rope thereon; the provision of a rope treating apparatus including a bath in which the rope is adapted to be treated and a wringer mechanism through which the rope passes after leaving the bath and which serves to remove excessive amounts of the bath material from the rope; the provision of a construction as last described in which the wringing mechanism comprises two pairs of rolls through which the rope passes and means for applying a greater pressure to the rope in passing through one pair of rolls than in passing through the other; the provision of a construction as last described in which the amount of pressure applied between the two pairs of rolls may be readily varied; and the provision of a construction as above described in which the proportional pressure applied by the two pairs of rolls may be readily varied with respect to each other.

Further objects of the invention include rope drying means comprising a pair of vertically spaced drums and means for passing a plurality of turns of rope about the drums, in combination with means for heating the rope during its passage over the drums to dry the same; the provision of a construction as above described in which the drums vary in diameter from one end to the other end thereof to compensate for the shrinkage of the rope in being dried; the provision of a construction as above described including means for maintaining the position of the runs of the rope during their travel over the drying drums; the provision of apparatus as above described including a pair of heating units one

2

arranged at each side of the runs of ropes passing over the drums, the heating units being bodily movable toward and from the drums whereby to render the drums readily accessible for applying a new run of rope thereto; the provision of a construction as above described in which the drums are supported in a frame and the heating units serve to close the opposite open ends of the frame; and the provision of a construction as above described in which the heating units each comprise an open sided hood-like structure each provided with a plurality of infra-red ray lamps arranged to direct the rays therefrom upon the runs of rope travelling over the drying drums and cooperating with the drum supporting frame to provide a substantially closed oven structure in which the runs of rope are confined.

The above being among the objects of the present invention the same consists in certain novel features of construction and combinations of parts to be hereinafter described with reference to the accompanying drawings, and then claimed, having the above and other objects in view.

In the accompanying drawings which illustrate a suitable embodiment of the present invention and in which like numerals refer to like parts throughout the several different views,

Fig. 1 is a perspective view taken from a side of our improved apparatus showing the same with the heating units in retracted or open position;

Fig. 2 is a diagrammatic view showing the path of movement of the ropes through the apparatus shown in Fig. 1;

Fig. 3 is an enlarged, fragmentary perspective view taken looking generally in the direction of the arrow 3 of Fig. 1 into the upper end of the treating or dipping tank;

Fig. 4 is a fragmentary vertical sectional view taken transversely through the treating or dipping tank shown in Fig. 3 as on the line 4—4 of Fig. 3;

Fig. 5 is an enlarged fragmentary, transverse sectional view taken on the line 5—5 of Fig. 1 and illustrating the means provided for maintaining a tension on the rope being fed to the drier;

Fig. 6 is an enlarged fragmentary, sectional view taken on the line 6—6 of Fig. 4 and illustrating in greater detail the construction of the wringer mechanism;

Fig. 7 is a transverse sectional view taken on the line 7—7 of Fig. 6; and

Fig. 8 is an enlarged, fragmentary, transverse sectional view taken axially of the drying rolls 55 as on the line 8—8 of Fig. 1.

The present invention deals with mechanism for treating or impregnating rope formed from vegetable fiber with any suitable preserving solution or compound and then drying such rope. In accordance with the present invention the rope is first passed through a bath of the preserving compound, preferably maintained at an elevated temperature to assist in the impregnation of the rope by the bath, the rope is then withdrawn from the bath and passed through wringers whereby to remove the excess solution or composition therefrom, it is then passed through a drying apparatus of novel construction to cause the rope to be quickly dried.

The rope is, of course, fed continuously through the apparatus and in passing through the bath of preserving solution or compound it is caused to travel in a plurality of turns over a pair of spaced parallel rolls submerged in the bath. These rolls are mounted on a frame which can be withdrawn from the bath to facilitate the application of a new run of rope thereon and to further facilitate the application of a new run of rope thereon the rolls are supported from the frame at one end only so as to leave the opposite ends unobstructed for the winding operation. The rope being withdrawn from the bath is passed through wringers of novel construction in order to remove excess solution or composition therefrom and is then passed in a plurality of turns over a pair of vertically spaced rolls during which it is applied to the rope in order to dry the solution or composition with which it has been impregnated.

The rope to be treated and indicated in the drawings generally at 10 is usually received from the rope manufacturer in the form of spools 12 as illustrated in Fig. 1. If desired these spools 12 may be mounted on a suitable rotatable support or spindle to permit the rope 10 to be readily reeled therefrom or if desired, and as has been found convenient, the spool 12 may be simply placed on end as illustrated in Fig. 1 in a position to permit the rope to be withdrawn axially upwardly therefrom. It will be understood that the rope 10 is of a conventional type formed from vegetable fibers, such as hemp or the like, and is to be treated by a preservative or other material the purpose of which may, for instance, be to protect the rope against rotting, mold, insect or other enemies, to increase its strength or for any one or more of these purposes. Such preservative materials are applied in liquid form and in most cases will be applied in the form of a solution of a solid dissolved in a suitable solvent. Accordingly, for the purpose of simplicity in description the impregnating material regardless of its character will hereinafter be referred to as an impregnating or treating solution. It will thus be understood that in order to protect the rope it first must be impregnated with such solution and then dried, and the purpose of the present invention is to provide a means by which this may be expeditiously accomplished.

In order to impregnate the rope with the solution the rope is withdrawn from the spool 12 and passed through a bath of the solution contained within a tank 14. This tank as brought out in Figs. 1, 3, and 4 consists of a tank having a sheet metal sides, ends and bottom and provided with angle iron corners 16 which project down below the bottom of the tank to provide legs which support the tank a material distance above the floor. The impregnation of the rope with the solution is facilitated by maintaining the

solution in a hot or warm condition but at a temperature, of course, below that at which a deleterious effect on the fibers of the rope may occur. While in the broader aspects of the invention any suitable means may be provided for maintaining the solution in the tank 14 at an elevated temperature, a preferable method is to mount a plurality of infra-red ray lamps such as 18 below the tank and within the area bounded by the legs 16, the lamps being arranged to direct the rays therefrom against the bottom wall of the tank thereby to heat the same. Preferably the infra-red ray lamps 18 are arranged with their faces projecting through a shield 20 so as to protect the wiring therefor below the shield against reflection of heat discharged by the lamps 18. In order to confine the heat discharged by the lamps 18 against the bottom of the tank 14 sheet metal shields or panels 22 are extended between the legs 16 from the bottom of the tank 14 to a point adjacent the floor as shown.

In order to properly impregnate the rope 10 with the treating solution it is, of course, necessary that the rope be immersed in the solution for an appreciable time element and the impregnation is also enhanced by working the rope while submerged in the solution. Both of these features are accomplished by providing a plurality of turns of the rope 10 about a pair of rolls 24 submerged in the solution so that each increment of length of the rope as it passes through the tank 14 is caused to travel over the developed length of all of the turns and in being bent repeatedly about the rolls is simultaneously worked.

The rolls 24 are arranged with their axes horizontal and parallel with each other and preferably on the same level with each other as shown. Each roll 24 is supported on a shaft 26 and the shafts 26 are supported at one end only in a frame which will now be described. This frame includes a pair of parallel and laterally spaced curved frame members 28 preferably of T-section as shown. The frame members 28 are arranged with the lower ends thereof directed vertically and with the upper ends thereof directed horizontally in the same direction as shown. The lower ends of the members 28 are rigidly secured together by means of a horizontally extending bar 30 rigidly secured to each thereof as by welding. The ends of the bar 30 project laterally beyond each of the frame members 28 and the shafts 26 project through the corresponding ends and are rigidly fixed thereto. As brought out in Fig. 4 the rear or left-hand end of the shafts 26 project outwardly beyond the bar 30 and beyond the rear edge of the frame member 28.

The upper free ends of the frame members 28 are connected together by means of a transversely extending angle member 32. Spaced outwardly from the angle member 32, or to the right as viewed in Fig. 4, is an elongated plate or bar member 34 forming an arm. As brought out in Fig. 3 the arm 34 is inclined downwardly to the right. Its lefthand end portion as viewed in Fig. 3 is rigidly fixed with respect to the angle member 32 by means of a bracket 36 fixed both to it and to the angle member 32 as by welding or the like. The opposite or righthand end of the arm 34 is rigidly fixed to the frame by means of an angle member 38, the rear or lefthand end of which as viewed in Fig. 4, is rigidly secured to the righthand frame member 28 as viewed in Fig. 3 and extends therefrom outwardly into con-

tact with the righthand end of the arm 24 to which it is rigidly secured by welding or the like. The outer end of the member 38 is braced from the angle 32 by means of a vertical member 40 between it and the angle member 32 and rigidly secured to both thereof as by welding or the like. The member 40 has an additional function which will hereinafter be brought out.

It will also be noted that below the angle member 38 and slightly below the plane of the upper edges of the rolls 24 an additional angle member 42 is extended outwardly in parallel relation with respect to the member 38 and is rigidly secured as by welding at its inner end to the same frame member 28 that the member 38 is secured to. The angle member 42 is provided with a plurality of preferably equally spaced pins 44 projecting upwardly from its upper surface to above the plane of the upper edges of the rolls 24. The purpose of the pins 44 is to guide the turns of 20 rope 10 passing over the rolls and to keep the various turns separated from each other axially of the rolls.

Positioned between the arm 34 and the angle member 32 is a channel sectioned arm 46 which is pivotally connected to the arm 34 for movement in a vertical plane about the axis of a pin or bolt 48 as best brought out in Fig. 6. The pin or bolt 48 carries a roller 49 (see Fig. 6) against which the rope being processed bears, and which is provided to prevent the rope from rubbing on the pin 48. As indicated in this last figure both the arms 34 and 46 are provided with a plurality of longitudinally spaced holes 50 therein through any cooperating pair of which the pivot pin 48 may be projected, the pin 48 in the particular arrangement illustrated in Fig. 6 being received in those pairs of holes closest to the lefthand end of the arm 34 and most remote from the righthand end thereof.

The lefthand end of the arm 34 carries a relatively narrow roll 52 for rotation about a horizontally extending axis perpendicular to the plane of thickness of the arm 34. A similar roll 54 is rotatably carried by the righthand end of the arm 34. A similar roll 56 is rotatably carried by the lefthand end of the arm 46 directly below the roll 52, and an additional similar roll 58 is rotatably supported by the arm 46 directly above the roll 54. It will be understood that the rolls 52 and 56 are arranged with their planes of thickness vertically aligned as brought out in Fig. 7 and the rolls 54 and 58 are similarly aligned. The rolls 52, 54, 56 and 58, as brought out in Fig. 7, are circumferentially grooved, such grooves being partially circular in section and preferably of a radius equivalent to the radius of the rope being treated.

It will be noted from an inspection of Figs. 3 and 4 that the arm 46 bears against the outer face of the member 40 serving to connect the angle 32 with the angle member 38 and the member 49 thus serves to aid in guiding the arm 46 in its pivotal movement about the pivot pin 48. As brought out in Fig. 3 the arm 46 projects to the right outwardly beyond the corresponding end of the tank 14 which end has fixed thereto a pair of spaced vertically extending angle irons 60 between which the arm 46 is relatively closely but slidably received, thereby to provide an additional means for guiding the arm 46 in its pivotal movements about the axis of the pin 48. As brought out in Fig. 1, the outer end of the arm 46 is provided with a weight 62 mounted thereon for slidable movement longitudinally thereof, a set 75

screw 64 being provided in the weight 62 for locking it to the arm 46 in any position of such adjustment. Shifting of the weight 62 on the arm 46 will vary the wringing action of the last-mentioned rolls on the rope passing between them. It will be understood that the effect of the weight 62 is to pivot the arm 46 in such direction as to cause the rolls 54 and 58 to be urged toward one another and the rolls 52 and 56 to also be urged toward one another.

As best brought out in Fig. 3 an angle iron 66 is fixed to the righthand end of the tank adjacent the near corner thereof and projects vertically therefrom. At its upper end it rotatably supports a sheave 68 arranged with its axis horizontal. Below the sheave 68 the angle iron 66 carries a bracket 70 provided with an opening 72 therein in vertical alignment with the outer or righthand edge of the sheave 68.

With the above described construction the rope 10 from the spool 12 is passed up through the opening 72 in the bracket 70, over the sheave 68, and then down under the righthand roll 24. From the righthand roll 24 it extends to and under the lefthand roll 24, and then upwardly around the lefthand roll 24 and across the top of the righthand roll 24, in repeated sequence, it thus being wound around the rolls 24 in a plurality of turns, shown in the drawings as seven by way of illustration. After passing up over the lefthand roll 24 the last time the rope 10 is led under the roll 54 and around the roll 54 between it and the roll 58, then between the rolls 52 and 56. A guard 73 carried by the righthand end of the arm 34 acts to prevent the rope 10 from becoming inadvertently disengaged from the roll 54.

The rope 10 is pulled through the apparatus above described and in passing over the rolls 24 the upper runs of the turns of rope are maintained in spaced relation with respect to each other by means of the pins 44 between which the upper runs extend. Because of the number of runs of rope on the drums 24 a relatively great length of rope is submerged in the solution within the tank 14, so that although the rope 10 may be withdrawn from the treating tank 14 at a relatively rapid rate each increment of length thereof is in fact subjected to the solution for a material length of time sufficient to result in the desired impregnation of the rope with the solution. The heating of the solution, of course, facilitates this impregnation as previously mentioned.

In withdrawing the rope 10 from the apparatus thus described the rope 10 in passing between the rolls 54 and 58 is squeezed and relieved of the bulk of the free solution which is clinging to it, and in further passing between the rolls 52 and 56 it is further squeezed to remove further amounts of the solution from the rope. Thus the rolls 54 and 58 and the rolls 52 and 56 act in the nature of wringer rolls to squeeze excess amounts of the treating solution from the rope thereby to facilitate the drying of the rope. In this respect it will be appreciated that under the conditions shown, and particularly with relation to Fig. 6 which indicates that the lever arms carrying the rollers 52 and 56 are considerably shorter than the lever arms carrying the rollers 54 and 58, a greater amount of pressure will be exerted on the ropes by the rolls 52 and 56 than by the rolls 54 and 58. This will usually be found preferable inasmuch as by the time the rope reaches the rolls 52 and 56 the greater proportion of the free solution clinging to the rope

will already have been removed by the rollers 54 and 58, and a more thorough wringing operation will, therefore, result. However, the wringing effect between the two pairs of rollers may be readily varied by shifting the pivot pin 48 from the set of holes 50 shown to either of the other sets of holes 50 to the right thereof so as to get any desired relation between the wringing effect of the two sets of rollers. In so shifting the pivot point at least some of the rolls will be required to be replaced by similar rolls of a different diameter so as to maintain both sets of rolls operative, but this is readily done.

Where operation of the apparatus is continuous then when the end of one spool of rope is reached the end of a new spool may be attached thereto and carried on through the apparatus in the same manner as if the rope was endless. Additionally, where it is desired to stop the operation of a machine for a material length of time without permitting the rope to soak in the treating solution a lead wire or dummy rope may be attached to the end of the last spool of rope to be treated and run through the length of the apparatus before the apparatus is stopped, the end of the next spool to be treated then being attached to the tail end of the lead wire or dummy rope when the apparatus is again started up to thus eliminate the necessity of re-threading the new rope through the apparatus. However, there are bound to be instances where it is necessary to re-thread a rope and to facilitate this threading operation and particularly to eliminate the necessity of draining the tank 14 under such conditions, the rolls 24 and their supporting and associated mechanism are preferably arranged as a unit capable of being readily and bodily removed from the tank 14.

In order to accomplish this last feature and as best brought out in Fig. 3 a pair of angle irons 74 are secured to the inner faces of the side walls of the tank 14 in line with each end of each of the shafts 26, the angle irons of each pair being arranged in back-to-back relationship with their opposed flanges in parallel relation with respect to each other and spaced from one another by a distance slightly greater than the diameter of the shafts 26. The shafts 26 are of a length slightly less than the width of the tank 14 and the ends of the shafts 26 are received between the flanges of each of the corresponding pairs of angle irons 74 which thus serve as vertical guides therefor. Therefore, each unit comprising the rolls 24, the supporting frame therefor, the arms 34 and 46 and all interconnected parts are vertically removable from the tank 14 and are likewise receivable therein. Advantage of this construction is taken in order to locate this unit at a predetermined vertical position in the tank 14 and this means comprises angle shaped brackets 76 which are suitably fixed as by welding or the like within the channel provided by each cooperating pair of angle irons 74 at a distance above the bottom of the tank at which it is desired to locate the shafts 26. This is brought out in Fig. 4. It will also be appreciated that the provision of the brackets 76 serve in a measure as a means for supporting the free ends of the shafts 26 during operation. Cooperation between the ends of the shafts and the angle irons 74 positively lock the unit against movement longitudinally of the tank 14. Preferably the angle member 32 is provided with a hole or slot 78 therein by means of which a hook such as 80, illustrated in Fig. 4, and carried, for instance,

by a chain fall or the like may be attached to the unit for raising it out of the tank 14 or for depositing it therein.

It is to be particularly noted that when the unit thus described is removed from the tank 14 the outer ends of the drums 24 are free and unrestricted by cross-members or the like so that a workman may project his hand into the unit and over and under the rollers 24 to thread the rope 10 thereon in a quick and easy manner.

After the rope 10 has been impregnated by the solution in the tank 14 and then passed through the wringing rolls it is then passed to the drier portion of the device. This portion of the device may, if desired, be fixed with respect to the tank 14 so as to form a unitary part of the impregnating part of the apparatus. As brought out in Figs. 1 and 8 the drier portion comprises a framework consisting of a pair of laterally spaced and parallel bottom angle members 100 which may be suitably supported as, for instance, directly upon the floor as shown in Fig. 1. The angles 100 are arranged with one flange in flat contacting relationship with respect to the floor or other supporting surface and the remaining flange at the outer edge thereof and directed vertically as best brought out in Fig. 8. The angle members 100 are suitably connected together in fixed relationship by means of a plurality of cross-members 102 extending therebetween and fixed to both thereof. Midway the length of each angle member 100 and fixed to the inner face of the vertically directed flange thereof as, for instance, by welding or the like is a vertically directed plate member 104, the plate members 104 being transversely aligned with one another and extending in parallel relation with respect to each other. The plates 104 may be rigidly connected together across their top by means of a plate member such as 106 arranged with its plane of thickness horizontal as shown in Fig. 1 thus to serve as a motor support as will hereinafter be more clearly brought out. Each plate member 104 has fixed to its outer face a pair of bearing blocks 108, the block 108 on each plate 104 being vertically spaced from and vertically aligned with each other, the lower blocks 108 on both plates 104 being axially aligned with each other as are the upper blocks 108 on each plate member 104.

Rotatably supported between each aligned pair of bearing blocks 108 is a shaft 110. Carried by each shaft 110 is a drum 112 fixed thereto for equal rotation therewith. Thus the drums 112 are vertically aligned with one another.

Each plate member 104 has its upper end braced with respect to the angle members 100 by means of angle members 114. Each angle member 114 is connected at its upper end to the upper end of the corresponding plate member 104 and extends at an angle downwardly and away from the plate member 104 to a point at or adjacent the corresponding outer end of the corresponding angle member 100 to which it is suitably fixed. Preferably the upper ends of the plate members 104 are cut away on an angle corresponding with the angle of the brace members 114 and plate members such as 116 extend between the plate members 104 across such angular portions as illustrated in Fig. 1, not only to serve with the plate 106 as a roof over the drums or rolls 112 but also to aid in rigidifying the structure.

In vertical alignment with each angle member 100 and at a point slightly below the axis of the upper shaft 110 an angle member 118 is extended

horizontally, as viewed in Fig. 1, from the left-hand members 114 to the right beyond the end of the angle members 100. There outer or right-hand ends as viewed in Fig. 1 are supported by vertical legs 120 one of which extends upwardly from the corresponding end of each of the angle members 100 and is rigidly secured to both. A diagonal brace member 122 serves to brace the righthand ends of the angles 118 against lateral movement. The extreme righthand ends of the angles 118 are braced by angle members 124 extending from their outer ends to the legs 120 at a point below the upper ends of the latter. The righthand or free ends of the angles 118 are also braced by an interconnecting angle member 126 which also serves an additional purpose which will hereinafter be explained.

It will be noted and as brought out in Fig. 1 that the drying apparatus is arranged with its length parallel to the length of the tank 14 and with the last described ends of the angle members 118 overlying the adjacent end of the tank 14. The adjacent end wall of the tank 14 is extended upwardly as at 128 to a point adjacent the angle members 118 to serve as a shield and the far side of the tank member 14 as viewed in Fig. 1 is similarly extended as at 130 for the same purpose.

Rotatably supported upon the angles 126 at the righthand end of the angles 118 at the upper end of the framework for the drying mechanism and substantially vertically above the wringer rolls 52 and 56 and at the far side of the framework as illustrated in Fig. 1 is a sheave 132 over which the rope 10 from the wringer rolls 52 and 56 is trained. The rope in passing over the sheave 132 extends toward the center of the drying apparatus and is trained over another sheave 134 located immediately above the upper roll or drum 112 adjacent the far end thereof as viewed in Fig. 1 and in a position to feed the rope 10 thereover downwardly to the near edge or side of the upper drum 112 as viewed in Fig. 1. This particular run of rope is housed in a suitably supported downwardly opening channel sectioned housing 135.

From the sheave 134 the rope 10 extends downwardly and then is wound around the drums 112 in a plurality of loops and finally is led off of the upper drum to a sheave 136 suitably mounted on the righthand plate member 116, a hole 138 being provided in such plate member 116 to permit the passage of the rope therethrough. The rope 10 extends horizontally to the right as viewed in Fig. 1 from the sheave 136 over a sheave 140 fixed to a shaft 142 rotatably supported by a bracket 144 fixed to and projecting upwardly from the angle member 126 connecting the free ends of the angles 118. From the sheave 140 the rope 10 may be directed to any suitable point of reception, here shown as a barrel 146 positioned on the floor immediately below the sheave 140 and into which the rope 10 may be coiled as it is discharged from the apparatus.

The rope is caused to travel through the apparatus described in the following manner. On the top plate 106 of the drying portion of the apparatus an electric motor 150 is mounted and drives through a speed reducing mechanism including chains 152 and 154 and a pair of cooperating sprockets, indicated generally at 156 and rotatably mounted upon the plate 106, to a sprocket 158 which as best illustrated in Fig. 8 is fixed to the righthand end of the upper shaft 110, thereby to drive the shaft 110 and its corresponding drum or roll 112. As brought out in Fig. 8 each shaft 75

110 has preferably fixed thereto a smaller sprocket 160 in vertical alignment with each other and connected together by means of a chain 162. Thus the shafts 110 and their drums or rolls 112 are driven at uniform speeds of rotation and inasmuch as they are of identical size and construction, at corresponding peripheral speeds. The friction of the various turns of rope 10 on the drum rolls 112 is sufficient to draw the rope 10 through the mechanism in the tank 14 previously described and to cause it to travel about the drums or rolls 112.

In order to keep the rope 10 relatively taut on the drum rolls 112 the sheave 140 is rotated 15 at a slightly greater peripheral speed than the peripheral speeds of the drums or rolls 112 and this is accomplished as follows. As brought out in Fig. 1 the near end of the upper shaft 110 projects through the corresponding plate 104 and 20 has mounted thereon a pulley 164. The near end of the shaft 142 which carries the sheave 140 has mounted thereon a pulley 166 which is of a smaller diameter than the pulley 164. A cross-belt 168 connects the pulleys 164 and 166 thereby to drive 25 the pulley 166 at a greater peripheral speed than the peripheral speeds of the rolls or drums 112.

In order to insure the sheave 140 exerting a constant pull on the rope 10 tending to withdraw it from the drums 112 an arm 170 is pivotally 30 connected at one end to the bracket 144 for movement in a vertical plane and in outwardly spaced relation with respect to the pivotal axis thereof carries a roller 172. The outer or free end of the arm 170 is provided with a weight 174 thereon 35 which tends to urge the roller 172 downwardly against the rope 10 passing over the sheave 140. As brought out in Fig. 5 the peripheral portion of the roll 172 is relatively narrow and tends to imbed the rope 10 passing over the sheave 140. 40 into the peripheral groove of the sheave 140 and thus increase the frictional engagement of the rope 10 therewith. Thus although the rope 10 must necessarily slip in the peripheral groove of the sheave 140 due to the greater peripheral speed 45 of the sheave 140 as compared to the peripheral speed of the drums 112, there is sufficient friction exerted between the sheave 140 and the rope 10 to constantly maintain the rope 10 between the sheave 140 and the drums 112 under tension. 50 As will be appreciated this has a tendency to prevent slack from developing in the various turns of rope around the drums 112.

The rope 10 in passing over the drums 112 is dried and in drying it necessarily shortens in 55 length to a material extent. In order to compensate for this shortening action the rolls or drums 112 and as brought out in Fig. 8 are tapered in diameter from their righthand end to their lefthand end as viewed in Fig. 8, that is from the end thereof which first receives the rope from the tank 14 toward that end thereof from which the rope is discharged in dry condition. The taper of the drums or rolls 112 is such, as determined from experience, as to maintain a 60 substantially constant tension on the various turns of the rope 10 about the drums or rolls 112 in spite of the shortening of the rope during drying. This is an important feature as it has been found that unless a substantially constant tension 65 on all of the turns of the rope passing over the drums or rolls 112 is maintained an unsatisfactory operation will result.

In order to maintain the various turns of rope 70 passing over the drums or rolls 112 in properly spaced relation with respect to each other axially

11

of the drums or rolls a pair of angle irons 180 are secured to the inner face of each of the plate members 104. The angles 180 secured to each plate member 104 are vertically directed and arranged with one flange thereof in flat contacting relationship with the corresponding plate 104 and the remaining flange thereof projecting inwardly therefrom. The angles 180 on each plate member 104 are spaced from each other horizontally by a distance slightly greater than the diameters of the drums or rolls 112. A bar member 182 is extended between the angles 180 on that side of the drums or rolls 112 where the turns of the rope 10 move downwardly, and it is located immediately above the lower drum 112. The bar member 182 is provided with a plurality of pins 184 which project inwardly therefrom to between the various turns of the rope 10 on such side of the drum. A similar bar member 196 is extended between the remaining angles 180 and adjacent the upper drum or roll 112 and is provided with similar pins 188 similarly projecting between corresponding turns of the rope 10.

While in the broader aspects of the invention the particular means employed for applying heat to the turns of rope 10 extending over the drums or rolls 112 is more or less immaterial, in accordance with a more limited phase of the present invention a novel means is provided for effecting this drying action. This means comprises a pair of units indicated in Fig. 1 generally at 190, one positioned on each side of the rolls 112. Each drying unit 190 comprises a framework enclosed, except at its bottom and that side facing the rolls 112, with a suitable sheathing and each is provided at its bottom with rollers 192 resting on the bottom flanges of the angle members 100. The rollers 192 support the units 190 for rolling movement on the angle members 100 toward and from the central portion of the device carrying the rolls or drums 112. Each unit 190 is provided with heating means for applying heat to the rope 10 on the rolls 112. In the particular case shown the heating means comprises a plurality of infra-red ray lamps 194 arranged to direct the rays therefrom towards the turns of rope over the rolls or drums 112. Each unit 190 is of such height and width that when it is rolled up into contact with the central portion of the device its inner edges cooperate with the plate members 104 to provide a substantially closed oven within which the turns of rope on the rolls or drums 112 are situated.

The faces of the infra-red ray lamps 194 in each unit 190 project through corresponding apertures formed in a sheet metal shield 196 mounted therein. As brought out in Fig. 1 the lower end of each shield 196 terminates short of the floor. As also indicated in Fig. 1 the sheathing for the back face of each unit 190 stops short of the upper end of such unit so as to provide an opening 198 through which air may enter the unit back of the corresponding shield 196. An exhaust fan 1980 mounted on the upper plate 106 and operatively connected to the motor 150 for driving movement therefrom has its suction connection connected into the space below the roof portion of the device so as to withdraw air therefrom. When the units 190 are moved up into operative relationship with respect to the plate members 104 so as to provide an enclosing oven for the turns of rope extending over the drums 112 and the fan 1980 is operated it serves to draw air through the openings 198, downwardly over the rear portions of the infra-red ray lamps 194 and the wiring therefor within each

12

unit 190, then under the lower ends of the shields 196 and upwardly around the turns of rope 10 on the drums or rolls 112, and is then exhausted from the device. Such air in passing down over the rear portions of the infra-red ray lamps 196 serves to cool and extract heat therefrom and this in connection with the heat applied to the turns of rope by the direct rays from the infra-red ray lamps 194 serves to quickly and effectively withdraw the volatilizable ingredient of the treating solution from the rope 10 and to effect a quick drying of the same, but without subjecting the rope 10 to such temperature as may adversely affect it.

It may be noted and as brought out in Fig. 1 that a control box 200 is preferably mounted upon the outer face of one of the members 104 and it is connected by a flexible cable 202 with the units 190, thus permitting the units 190 to be moved toward or from operative position without requiring the disconnecting of any circuits.

It will be appreciated that the ability to move the units 190 to and from operative relationship with respect to the various turns of rope passing over the rollers or drums 112 permits the drying apparatus to be opened up so that a workman may conveniently work on the rolls or drums 112 to thread the rope 10 about them, or to make any repair or adjustment on any portion of the device without interference from other portions thereof. This feature is, of course, of great convenience in the servicing of the drying apparatus shown.

Having thus described our invention, what we claim by Letters Patent is:

1. Rope treating apparatus comprising, in combination, a tank adapted to receive a body of rope treating liquid, a framework removably received in said tank, a pair of rolls, means for supporting said rolls on said frame in spaced and parallel relation with respect to each other, said means being connected at one end only to said frame whereby to leave the opposite ends of said rolls free.

2. In a rope treating apparatus, in combination, a tank adapted to contain a body of rope treating liquid, a pair of rolls rotatably mounted in said tank with their axes in spaced and parallel relation with respect to each other and over which a plurality of turns of rope are adapted to be wound, and wringer mechanism adapted to receive rope discharged from said rolls and remove excess liquid therefrom comprising a fixed arm carrying a wringer roll on each end thereof, a movable arm pivoted to said fixed arm intermediate the ends thereof, rolls on said second arm cooperating with said rolls on said first-mentioned arm to squeeze the rope passed therebetween, said second-mentioned arm having an extended end portion, and means cooperating with said extended end portion tending to urge the last-mentioned wringer rolls toward engagement with the first-mentioned wringer rolls.

3. In a rope treating apparatus, in combination, a tank adapted to contain a body of rope treating liquid, a pair of rolls rotatably mounted in said tank with their axes in spaced and parallel relation with respect to each other and over which a plurality of turns of rope are adapted to be wound, and wringer mechanism adapted to receive rope discharged from said rolls and remove excess liquid therefrom comprising a fixed arm carrying a wringer roll on each end thereof, a movable arm pivoted to said fixed arm intermediate the ends thereof, rolls on said second

arm cooperating with said rolls on said first-mentioned arm to squeeze the rope passed therebetween, said second-mentioned arm having an extended end portion, and means cooperating with said extended end portion tending to urge the last-mentioned wringer rolls toward engagement with the first-mentioned wringer rolls, said pivotal connection between said arms being closer to one cooperating pair of said wringer rolls than to the other thereof whereby to effect a more severe wringing action on the rope passing through one of said pair of wringer rolls than through the other thereof.

4. In rope treating apparatus, in combination, a tank adapted to receive a body of rope treating liquid, a frame removably received by said tank, a pair of rolls arranged with spaced parallel axes rotatably supported by said frame for submersion in said liquid in said tank, an arm fixed with respect to said frame above said rolls, a second arm pivotally mounted on the first-mentioned arm intermediate the ends thereof, cooperating pairs of wringer rolls carried by said arms on each side of said pivotal point of said second arm and between which rope discharged from the

5

first-mentioned rolls is adapted to pass, and means cooperating with the second-mentioned arm tending to urge said rolls toward contact with one another.
